WEFT-MOISTENING SHUTTLE.

1,101,712.

Specification of Letters Patent. Patented June 30, 1914.

Original application filed September 9, 1910, Serial No. 581,200. Divided and this application filed May 18, 1911. Serial No. 628,079.

To all whom it may concern:

Be it known that I, EMIL PREIN, mechanical engineer, a subject of the German Emperor, residing at Am Bokemahl 10^a, Hanover, Germany, have invented new and useful Improvements in Weft-Moistening Shuttles, of which the following is a specification.

The subject of the present invention is divided from the application dated September 9th, 1910, Serial No. 581,200, of which it originally formed a part.

As is well known, during the weaving of fabrics the fibers become loose from the 15 yarn, even when they have been first connected together by some preparation or are woven by the wet process. In the case of the fibers of the warp yarn, this takes place owing to the strong mutual friction during the formation of the shed and to the reciprocation of the reed; in the case of the fibers of the weft yarn, owing to the sudden cessation of the adhesion between the fibers caused during the picking of the 20 weft and by the very rapid unwinding of the yarn and by the attraction between the yarn remaining on the shuttle and that which is being unwound. The fibers which are then still projecting from the surface 25 of the fabric are removed by shearing, singeing and cleaning machines in order to make the fabric suitable for various purposes. In this way the fabric loses not only a large number of fibers which would otherwise 30 offer great resistance to tearing, but the weaving in of fibers which tend to become loose, and the violent removal of those which project, results in serious drawbacks. During shearing, the very sharp cutters which 35 work at high speed not only remove the projecting fibers but also cut little knots and threads off, which damage is not at first noticeable and only shows unfavorable results when the fabric is tested as to its 40 resistance to tearing as a completed length. In the singeing process it is the heat, generally acting suddenly on the fabric, which makes all the fibers brittle, more particularly the single cell cotton fibers. A further 45 important drawback is that the fibers which have been woven in a curved and crushed state, remain in the fabric with a spreading force which has not been weakened in any 50 way. If the woven material is treated later

on for any technical purpose the fibers become loose and project from the fabric as the spreading forces of the fibers and the adhering forces of the preparation act in opposition to each other. Even if the curved fibers and hairs are held during drying by 55 mechanical pressure, which, as is well known in practice, is carried out in different ways in various fabrics, according to the purpose for which they are intended, they are merely held fast but not weakened. They will also 60 in this case gradually become loose and detached from their bed owing to the irregular movement of the fabric, changeable temperature and varying strains set upon the 65 fabric with disadvantageous results. 70

The process and the apparatus of the present invention hereinafter described, is intended to avoid the drawbacks in question. This process is characterized in that the weft threads are rubbed with a moistened 75 pad or the like immediately before being woven into the fabric, in such manner that all fibers are caused to adhere straightened to their threads, in which position they are held by the threads when woven together. 80 It is therefore of especial importance that the laying down of the fibers takes place exactly at the place where, and at the moment when no further fiber loosening forces are brought to operate on the threads. As a 85 material for laying down the fibers, moistened rubber sponge may for instance be used.

The invention may be carried out in a 90 variety of ways.

One construction of apparatus according to this invention is illustrated in the accompanying drawing.

The shuttle *z* may be of any well known construction, but preferably slightly longer 95 as it has to contain several parts in addition to those it normally carries. It has two compartments *p* in which is arranged a pad *i*. One space *p* through which the thread leaving the cop *s* must pass, is adjacent to a liquid chamber *r*, from which it is only separated by a perforated plate *q*. The pad *i* in this space is therefore always kept moist. The pad *i* in the second space is not directly moistened by the liquid but serves to complete 100 the drawing out and laying down of the moistened fibers on the threads. The threads are led from the cops *s* through eyes 105

t in the sides of the spaces *p*. In order to enable the thread to be passed through the pads *i* these are divided so that the parts may be separated when the shuttle is opened, 5 and the thread passed through the holes. The weaving is effected in the usual manner. The picking of the weft threads is also effected in the well known manner. During the passage of the shuttle *s* through the shed, 10 the liquid from the chamber *r* is shaken up by the striking of the driver and thereby passes through the perforated plate *q* and into the space *p*. At the same time the yarn runs from the cop *s* through eyes into the 15 two superimposed compartments *p* and through the pads *i*. In the first space the fibers projecting from the threads are moistened and are also slightly rubbed; in the second space the fibers receive a final rubbing 20 so that all the fibers are laid down on the thread. Immediately the thread leaves the shuttle, that is at the instant when the fibers are adhering firmly to the thread, it is caught between the warp threads and held 25 fast, so that the fibers can no longer free themselves. When the woven material is dried the fibers are held fast. The fabric thus manufactured is better able to resist 30 mechanical strains than that manufactured in the usual manner and more particularly fulfills modern requirements, where it is important to have a smooth fabric as, for instance, those used in the manufacture of balloon fabrics.

35 What I claim is:

1. In an apparatus for treating the weft threads of a fabric, the combination of a shuttle for throwing said threads, and a moistened pad mounted upon said shuttle 40 for laying down the projecting fibers in one direction along said weft threads, immediately before the latter leave the shuttle.
2. An apparatus for treating the weft threads of a fabric immediately before they 45 are interwoven, consisting of a hollow shuttle, a pad carried by said shuttle, means for keeping said pad moist, and means whereby

the weft thread is passed along the pad in one direction to lay down the projecting fibers. 50

3. An apparatus for the production of woven fabrics in which the projecting fibers are straightened out on the weft threads consisting of a shuttle, a moistened pad on said shuttle, a chamber carrying liquid and 55 means whereby the moistened pad is rubbed against the weft threads.

4. An apparatus for the production of woven fabrics in which the projecting fibers are straightened out on the weft threads, 60 consisting of a shuttle, a moistened pad on said shuttle, a chamber containing liquid, a perforated plate separating the pad from the liquid and means whereby the moistened pad is rubbed against the weft threads. 65

5. An apparatus for the production of woven fabrics in which the projecting fibers are straightened out on the weft threads, consisting of a shuttle, a moistened pad on said shuttle, a chamber containing liquid, a 70 perforated plate separating the pad from the liquid, a second pad, and means for guiding the weft thread through the two pads.

6. An apparatus for the production of 75 woven fabrics in which the projecting fibers are straightened out and laid down on the weft threads, consisting of the combination of a shuttle with suitably disposed eyes, a moistened pad carried by said shuttle, a 80 chamber containing liquid, a perforated plate separating said pad from the liquid in said chamber, and a second pad so disposed in said shuttle that the weft thread is directed by the eyes in the shuttle through the 85 two pads and out of the shuttle.

In testimony whereof I have signed my name to this specification in the presence of two subscribing witnesses.

EMIL PREIN.
